UNITED STATES PATENT OFFICE.

CHARLES A. LIEB AND CHARLES L. HEINS, OF NEW YORK, N. Y., ASSIGNEES TO SAID HEINS, AND JOHN H. LEE, OF NORWALK, CONNECTICUT.

IRONING-MACHINE.

SPECIFICATION forming part of Letters Patent No. 340,225, dated April 20, 1886.

Application filed October 31, 1884. Serial No. 146,892. (No model.)

To all whom it may concern:

Be it known that we, CHARLES A. LIEB and CHARLES L. HEINS, of the city and State of New York, have invented an Improvement in 5 Ironing-Machines, of which the following is a specification.

This invention is an improvement upon that set forth in our application No. 142,191, filed September 4, 1884; and it relates to the peculiar construction of the ironing-cylinder and to the device for applying pressure to the iron and holding the same while the work is being done.

In the drawings, Figure 1 is a vertical section longitudinally of the cylinders and through part of the standard. Fig. 2 is a cross-section of the ironing-cylinder. Fig. 3 is a side view of the lever for moving and clamping the shaft supporting the revolving iron. Fig. 4 is a section at the line $x x$. Fig. 5 is an end view of a portion of one head of the lower roller, and Fig. 6 is an elevation of the lever shown in Fig. 3.

The base a , standard b , and bearings c and 25 for the shaft e are similar to those in our aforesaid application, so, also, is the tubular box h , at the top of the standard b , and the shaft i , which passes through said standard and is bent outside the bearing, and the part 2 receives the ironing-roller l with the tubular hub 5, to revolve freely upon such shaft.

The shaft e is provided with the handle e' , by which it and the cylinder f are revolved. This cylinder f is supported by the two heads 35 $f' f''$, the edges of which are beveled or conical, and they receive between them the sheet-metal sleeves of the cylinder. These sleeves $f^3 f^4$ are each of sheet metal, of suitable thickness, and the inner cylinder is of a size to 40 fit closely within the outer cylinder. These sheet-metal sleeves $f^3 f^4$ are to be contracted, so as to be of a smaller diameter, by lapping the edges of the respective cylinders, and one cylinder is within the other, then the 45 said cylinders are introduced into the seamless tube forming the woven or knitted surface upon which the material to be ironed is laid. The conical heads are applied to the 50 ends of the cylinders and the sheet metal expanded by forcing the conical heads toward each other until the lapped portions pass clear

of each other and the abutting edges of the sheet metal come together, the longitudinal separation of the outer cylinder being at the opposite side to the longitudinal separation of 55 the inner cylinder, so that the cylinders mutually support each other and the elastic or woven surface upon the same.

The head f' is held from moving endwise upon the shaft e by the collar e^2 , and there is 60 a screw-thread upon the shaft e , near the end within the hub of the head f' , and the heads may be revolved, or the shaft is turned while the heads are held stationary, and one head is thereby screwed toward the other head, and 65 the conical surfaces of the heads expand the sheet-metal cylinders and stretch the woven bag, forming the surface of the cylinder, as aforesaid.

The hub k of the head f' is split longitudinally, and it is provided with projecting ears m , for the clamp-screw n to pass through, so that by tightening such screw after the cylinders have been expanded the hub will be made to clamp the screw portion of the shaft 75 and connect the cylinder and its shaft firmly.

The ironing-cylinder l is heated by a gas-flame or otherwise, and it is free to be revolved upon its shaft by contact with the material that is being ironed upon the bed-cylinder f . 80

The shaft i is bent or crank-shaped, the portion 2 being eccentric to the part that passes through the portion h of the standard.

There is upon the shaft i , adjacent to the 85 standard b , a split shell, s , the edge of which surrounds a cylindrical flange, b' , upon the tubular upper part, h , of the standard b , and the hub s' of this shell is clamped rigidly to the shaft i . There is a lever, t , having an 90 opening in it, so that the lever passes at each side of the hub s' , and the pivot-pin t' passes through the two parts of the lever and through the hub, but at one side of the shaft. The long end of this lever is made as a handle, t^2 , and the short end is made with a box or fork, t^3 , the inner faces of which are slightly tapering, and upon the edges of the shell s there are lugs s^4 , projecting one at each edge of the split or saw-cut in such shell s , so that 100 by swinging the lever upon its fulcrum the fork t^3 presses against the outer surfaces of

the lugs s^4 and springs the split shell sufficiently to cause it to clamp the cylindrical flange b' and hold the parts so that the shaft i cannot turn. The object of this construction 5 is to allow the attendant to grasp the handle t^3 and partially rotate the hub s' , shell s , and shaft i and by the crank or eccentric portion of the shaft i apply the necessary pressure of the ironing-cylinder to the goods upon the bed-cylinder, and then by a lateral movement or 10 swing of the lever upon its pivot to cause the fork t^4 to close the split shell, grasp the stationary cylindrical flange, and hold the parts firmly in position while the bed cylinder is 15 being revolved and the ironing performed. The reverse movement releases the parts, and it is preferable to employ a coiled spring, v , within the cylindrical flange b' , with one end passing into a hole in the standard b and the 20 other end into a hole in the hub s , so that the expansion of the spring will partially turn the shaft i and lift the ironing-cylinder off its work.

We do not herein claim the devices set forth 25 in our aforesaid application No. 142,191, filed September 4, 1884—viz., the hollow cranked shaft supporting the ironing-cylinder and a lever for partially turning the shaft, a spring

for turning the shaft the other way, and a gas-burner within the cylinder.

30

We claim as our invention—

1. The combination, with the conical heads f', f^2 and shaft e , of the two sheet-metal cylinders, one within the other and split lengthwise, and the fibrous covering for the bed-cylinder, the latter being expanded by the sheet-metal cylinders, and the conical heads acting 35 upon the same, substantially as set forth.

2. The combination, with the ironing-roller and its crank-shaped shaft, of a standard having a tubular box, h , at its upper end supporting the shaft, a cylindrical flange, b' , upon the box h , a split shell with projections upon it, a hub by which the shell is attached to the shaft, and a lever pivoted upon the hub for 40 moving the shaft, and a fork, t' , of the lever for tightening the split shell upon the cylindrical flange, substantially as set forth.

Signed by us this 29th day of October, A. D. 1884.

CHARLES A. LIEB.
CHAS. L. HEINS.
